J. J. L. Wright

UNITED STATES PATENT OFFICE

CLEVELAND CAPRIO, OF HAWLEY, PENNSYLVANIA

STARTING GAUGE FOR LOOMS

Application filed April 17, 1929. Serial No. 355,938.

This invention relates to a starting gauge for a loom, the general object of the invention being to provide indicating means to insure accurate positioning of the weft line or fell 5 when restarting the loom after the same has been stopped to remedy a fault, so as to insure an even and uniform weaving without showing any lay mark which would tend to mar the texture of the finished fabric.

10 Another object of the invention is to make the slide of two parts which are hingedly connected together so that the outer part can be swung out of the way of the batten when the device is not being used.

15 This invention also consists in certain other features of construction and in the combination and arrangement of the several parts, to be hereinafter fully described, illustrated in the accompanying drawings and specifically pointed out in the appended claims.

20 In describing the invention in detail, reference will be had to the accompanying drawings wherein like characters denote like or corresponding parts throughout the several views, and in which:—

25 Figure 1 is a sectional view through a portion of the loom, showing the invention in use.

Figure 2 is a top plan view.

30 Figure 3 is an enlarged top plan view of the invention.

Figure 4 is a section on line 4—4 of Figure 3.

35 Figure 5 is a section on line 5—5 of Figure 3.

Figure 6 is a section on line 6—6 of Figure 3.

Figure 7 is a view of the supporting plate.

40 Figure 8 is a view of the slide carrying plate.

Figure 9 is a view of one of the bolts for attaching the slide to its supporting plate and said plate to the main plate.

45 In these drawings, the numeral 1 indicates the breast beam of a loom and 2 the batten, and the numeral 3 indicates a supporting plate fastened to the top of the breast beam, this plate being of substantially L shape, with 50 an arc-shaped dial 4 adjacent the end of the

small arm of the plate. A plate 5 is adjustably secured to the small arm of the plate 3 by means of the bolts 6 passing through the slots 7 in the plate 5, each bolt having an enlarged rectangular shaped central part 8 55 which engages the wall of a slot 7, with its lower threaded end threaded into a hole in the plate 3 and its upper end receiving a nut 9, so that by loosening the nuts, the plate 5 can be adjusted on the plate 3. The inner 60 end of the plate 5 is formed with a perforated upstanding lug 10. The slide is shown at A and is composed of the sections 11 and 12 which are hingedly connected together, as shown at 13, the adjacent ends of the sections being formed with depending flanges 14 which act to hold the section 12 in horizontal position when said section 12 is in operative position. The section 11 is provided with a slot 15 through which passes the bolts 16 which are made similar to the bolts 6, these 65 bolts 16 having their lower ends engaging threaded holes in the plate 5 so that the slide A is adjustably connected with the plate 5. 70

A stem 17 is connected with the inner end of the slide and passes through the perforation in the ear 10 and has its free end threaded to receive a cap 18 so that the cap is adjustably connected with the stem and this cap bears against the short end of an arrow 19 pivoted on the plate 3 and having its pointed end arranged over the dial 4. A spring 20 connects the arrow with a part 80 of the plate 3 and acts to hold the small end of the arrow against the cap. A spring 21 is arranged on the stem between the ear and a part of the slide. This latter spring is designed to hold the slide in place while making adjustments, and by having the cap on the stem of the slide engaging the short end of the arrow, with the pivotal point of the arrow arranged as shown, insures a finer adjustment at arrow point. The plate 5 can be adjusted to suit the loom on which the device is used and by having the hinged section 12 on the slide, this part can be folded 85 out of the way when the loom is in operation.

If a fault should occur in the cloth, the loom is stopped and the parts of the device 90 95 100

are adjusted to cause the arrow to point at zero or the center line of the scale when the end of the section 12 is at the fell line. Then the part 12 is turned back and the fault corrected as usual, and then the section 12 is swung into operative position so that the fell line can be arranged at the proper point.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A starting gauge for looms comprising a supporting plate of angle shape having a dial adjacent one end of one of its arms, a plate adjustably arranged on the other arm, a slide carried by said other plate, a finger pivoted to the first plate and cooperating with the dial, an adjustable member connected with the slide and engaging the finger for causing movement of the finger by the movement of the slide and a spring on the part of the slide tending to hold the same in its outward position.

2. A starting gauge for looms comprising a supporting plate of angle shape having a dial adjacent one end of one of its arms, a plate adjustably arranged on the other arm, a slide carried by said other plate, a finger pivoted to the first plate and cooperating with the dial, an adjustable member connected with the slide and engaging the finger for causing movement of the finger by the movement of the slide, a spring on a part of the slide tending to hold the same in its outward position, said slide being formed of two parts which are hingedly connected together.

3. A starting gauge for looms comprising a supporting plate having a dial thereon, a finger pivoted to the plate and cooperating with the dial, a slide supported on the plate and having a hinged outer section, said slide being arranged at rightangles to the finger, a stem on the inner end of the slide, an adjustable part on the stem for engaging the finger whereby movement of the slide will operate the finger and a spring for normally holding the slide in its outward position.

In testimony whereof I affix my signature.

CLEVELAND CAPRIO.
